UNITED STATES PATENT OFFICE.

GEORGE A. LUTZ, OF NEW YORK, N. Y., ASSIGNOR TO AMERICAN CIRCULAR LOOM COMPANY,
OF PORTLAND, MAINE, A CORPORATION OF MAINE.

ELECTROPLATING APPARATUS.

No. 881,811.

Specification of Letters Patent. Patented March 10, 1908.

Original application filed April 8, 1907, Serial No. 366,903. Divided and this application filed August 8, 1907.
Serial No. 387,669.

To all whom it may concern:

Be it known that I, GEORGE A. LUTZ, a citizen of the United States, and resident of New York city, borough of Brooklyn, in the 5 county of Kings and State of New York, have invented certain new and useful Improvements in Electroplating Apparatus, of which the following is a specification.

This application is a division of my application for patent for electro-plating apparatus, filed April 8, 1907, Serial No. 366,903, and the object of the invention is to provide means for electro-plating a number of articles simultaneously to enable said articles to 10 be quickly immersed in and removed from the electrolyte or bath and to simultaneously immerse and remove one or more anodes, my invention having particular reference to galvanizing a plurality of pipes simultaneously, 15 such as conduits for electric conductors.

My invention comprises a suitable tank for the electrolyte or bath, means for suspending an exterior anode or series of anodes, a cathode adapted to support articles to be 20 plated and means for suspending one or more anodes from said cathode and insulated therefrom and I also connect said anodes electrically in the circuit.

My invention also comprises the novel details of improvement more fully hereinafter set forth and then pointed out in the claims.

Reference is to be had to the accompanying drawings forming part hereof, wherein— Figure 1 is a plan view of an electro-plating apparatus embodying my invention. Fig. 2 is a cross section substantially on the line 2, 2 in Fig. 1. Fig. 3 is a detail plan of the cathode plate, the contact for the interior anodes being removed. Fig. 4 is an enlarged vertical section through the cathode plate and its anodes. Fig. 5 is a section on the line 5, 5 in Fig. 4; and Fig. 6 is a section of the interior anode contact or ring.

In the accompanying drawings, in which similar numerals indicate corresponding parts in the several views, the numeral 1 indicates a suitable tank within which the several series of anodes 2, 3 are suspended. Tank 1 is shown provided on its upper edge with a 45 metal rim 4 shown provided with a binding

post 5 for connection with a line wire 6, and suitable hooks 7, which support the anodes 2 within tank 1, rest upon and make electrical contact with rim 4.

At 8 is a cathode plate of suitable metal, shown adapted to fit within tank 1 and from which the articles 9 are to be suspended in the electrolyte in the tank, which cathode plate is shown of such diameter as to permit it to pass between the outer series of anodes 2 and their hooks 7. The cathode plate 8 is shown provided with a series of threaded apertures 8^a, on its under surface, to which pipes 9 to be plated may be screwed so as to depend from cathode 8 in the electrolyte in the tank 60 between the several series of anodes 2, 3. I have shown the pipes 9 as arranged in circles, one within another, around anodes 3 and within the series of anodes 2, with suitable spaces between said pipes to permit the 65 ready plating of said pipes over their exterior surfaces.

At 10 is a suitable eye bolt or support connected with cathode plate 8 whereby the latter may be raised or lowered. 75

I have shown the anodes 3 suspended from cathode plate 8 and insulated from said plate, for which purpose said anodes are hung upon hooks 12, shown bent at both ends, and which are insulated from plate 8 as by insulating blocks 13 set in holes in said plate and provided with openings receiving said hooks, which blocks are shown provided with flanges 13^a resting upon plate 8, the upper bent ends 12^a of said hooks resting upon said 80 blocks whereby said hooks are insulated from said plate. Anodes 3 are shown provided with holes 3^a receiving the lower bent ends of hook 12, whereby said anodes may be readily connected with and disconnected 85 from said hooks. The anodes 3 are to be placed in circuit with the anodes 2 and for this purpose I have shown a contact or metal ring 14 resting upon hooks 12 and shown provided with a binding post 15 connected 90 by wire 16 with rim 4, as by a post 17 thereon. One or more of the hooks 12 may have pins 12^c passing through holes 14^a in contact 14 to keep said contact in proper position upon 95 said hooks, and said contact is shown pro- 100

vided with an opening 14^b (see Fig. 6) through which eye-bolt 10 passes. Cathode plate 8 is shown provided with a binding post 18 for connection with a line wire 19.

5 In electro-plating by means of my improvements, the anodes may be hung in series (one series within the other) upon their respective hooks 7 and 12, and the pipes or articles 9 to be plated will be attached to cathode 8 from 10 which anodes 3 are also suspended, which plate will then be lowered to immerse said pipes or articles and anodes 3 in the electrolyte in tank 1, and the current from the line wire will flow through the several anodes and 15 thence through the electrolyte, the articles 9 and cathode 8 to the line 19, and when the articles to be plated have been plated the cathode 8 with the attached articles and anode 3 will be removed and a new set of 20 articles attached to said plate and lowered into the electrolyte for plating. Each time that the cathode plate 8 is raised from the tank the anodes 3 suspended therefrom may be inspected and replaced as required upon 25 hooks 12, whereby the condition of said anodes may be frequently and readily determined.

By means of my improvements a relatively large number of articles may be attached to 30 the cathode plate for simultaneous plating and simultaneous removal from the electrolyte, and thereby a large number of articles and of considerable size, such as iron pipes for electric conduits, may be quickly handled 35 for electro-plating. Pipes may be readily galvanized in my apparatus by means of zinc anodes, and by suspending the articles 9 between the exterior and interior series of anodes the exterior surfaces of such articles 40 may be uniformly galvanized.

The articles 9 may be suspended from cathode plate 8 in any other suitable manner, and other changes may be made within the scope of the appended claims without departing from the spirit of my invention.

Having now described my invention, what I claim is:—

1. The combination of a tank for an electrolyte, means for suspending an anode 50 therein, a cathode, means for suspending an article to be plated therefrom, means for suspending an anode from said cathode, and means for insulating the anode from said cathode.

55 2. The combination of a tank for an electrolyte, means for suspending an anode therein, a cathode, means for suspending an article to be plated therefrom, and an anode suspending device carried by and insulated 60 from said cathode.

3. The combination of a tank for an electrolyte, means for suspending an anode therein, a cathode, means for suspending an

article to be plated therefrom, and a hook carried by and insulated from said cathode.

4. The combination of a tank for an electrolyte, means for suspending an anode therein, a cathode, means for suspending an article to be plated therefrom, an insulating block carried by said cathode, and a hook supported by said block to sustain an anode.

5. The combination of a tank for an electrolyte, means for suspending an anode therein, a cathode, means for suspending an article to be plated therefrom, a hook carried 75 by and insulated from said cathode, and a contact connected with said hook.

6. The combination of a tank for an electrolyte, means for suspending an outer series of anodes within the tank, a cathode having 80 means for suspending articles to be plated, and means carried by said cathode and insulated therefrom for suspending anodes within the first named series of anodes.

7. The combination of a tank for an electrolyte, means for suspending an outer series of anodes within the tank, a cathode having 85 means for suspending articles to be plated, insulators carried by said cathode within said series of anodes, and anode suspending devices carried by said insulators.

8. The combination of a tank for an electrolyte, means for suspending an outer series of anodes within the tank, a cathode having 90 means for suspending articles to be plated, 95 insulating blocks carried by said cathode, hooks supported by said blocks and suspending anodes within said series of anodes, and a contact connected with said hooks.

9. The combination of a tank for an electrolyte, means for suspending an outer series of anodes within the tank, a cathode having 100 means for suspending articles to be plated, insulating blocks carried by said cathode and having openings, hooks supported by said 105 blocks and passing through said blocks, anodes hung on said hooks, and a contact connected with said hooks.

10. The combination of a tank for an electrolyte, means for suspending an outer series 110 of anodes within the tank, a cathode having means for suspending articles to be plated, anode suspending devices carried by and insulated from said cathode, a contact connected with said devices and provided with 115 an opening, and means for suspending said cathode through said opening in said contact.

11. The combination of a tank for an electrolyte, means for suspending an outer series 120 of anodes within the tank, a cathode having means for suspending articles to be plated, a series of anodes suspended from said cathode and insulated therefrom, and means for connecting the first and second named anodes in series.

12. The combination of a tank having a

metal rim, hooks on said rim, anodes suspended from said hooks, a cathode having means to suspend articles to be plated, hooks carried by said cathode and insulated therefrom, and means for electrically connecting said cathode hooks and said rim in a circuit.

Signed at New York city, in the county of

New York, and State of New York, this 2nd day of August A. D. 1907.

GEORGE A. LUTZ.
